UNITED STATES PATENT OFFICE.

WILLIAM KRETER AND CHARLES KRETER, OF NEW YORK, N. Y.

PIANISSIMO DEVICE FOR PIANO-ACTIONS.

SPECIFICATION forming part of Letters Patent No. 785,005, dated March 14, 1905.

Application filed October 13, 1904. Serial No. 228,375.

To all whom it may concern:

Be it known that we, WILLIAM KRETER and CHARLES KRETER, citizens of the United States, residing at Manhattan, city and State 5 of New York, have invented new and useful Improvements in Pianissimo Devices for Piano-Actions, of which the following is a specification.

This invention relates to a pianissimo device for piano-actions which is simple of construction, readily accessible, and permits of ready adjustment.

In the annexed drawings, Figure 1 is a side elevation of a piano-action embodying this 15 invention. Fig. 2 shows the parts of Fig. 1 in pianissimo or soft position. Fig. 3 shows a modification.

The letter *a* represents a key, and *b* is the capstan screw or device. To a rail or fixed 20 point *c* is pivoted a link *e'*, also pivoted to the sticker or abstract *e*. The elbow-piece *d* is shown interposed between the capstan-screw and the abstract.

The elbow-piece *d* is shown with a recess 25 or socket into which the abstract can sit. This socket or seat retains the abstract in proper position relative to the elbow-piece *d*, so that while the parts can be separated or lifted apart and reassembled, yet the abstract 30 and elbow-piece cannot shift accidentally. When the key lifts the elbow-piece *d*, the latter raises the abstract and actuates the wippen *f* and also the jack and hammer, as shown.

The elbow-piece is shown jointed at *g'* to a 35 lever or finger *g*, having pivot connection *g'* with the abstract or action and resting upon transverse rod *h*. The rod *h* is connected by link *k* with hammer-rail *i*, and when the rail is moved by soft-pedal rod *o* to pianissimo position the rod *h* swings the finger *g* about pivot *g'* and lifts the abstract, as seen in Fig. 2, to compensate the action or maintain the relative position of the jack to the hammer.

The rod *h* by links *j* is connected or jointed 45 to a suitable part of the frame or a rail. The set-screws *p* allow adjustment of parts as required.

In Fig. 3 the elbow-piece *d* has its pivot connection *g'* at the front or opposite side of 50 the abstract as compared with Fig. 1. The ab-

stract, as seen, has a link *e'* pivoted to a fixed point and maintaining the abstract in alignment or proper position. The elbow-piece is linked to the abstract, but is detached or freely movable with respect to the action— 55 that is, said elbow-piece is loose or has no fixed fulcrum or pivot. The foot or bottom portion of said elbow-piece being supported on the capstan screw or device rises or moves with the key, and the fulcrum or pivot *g'* partakes 60 of the rise and fall. The link *k* is shown adjustably connected to the hammer-rail, so that the parts can be set as required.

What we claim as our invention, and desire to secure by Letters Patent, is— 65

1. A pianissimo device for piano-actions composed of a key, a capstan device, an elbow-piece having a foot that is supported upon the capstan device, and a lever pivoted to the elbow-piece and operatively connected to the 70 action, substantially as specified.

2. A pianissimo device for piano-actions composed of a key, a capstan device, an elbow-piece having a foot that is supported upon the capstan, a lever pivoted to the elbow-piece, an 75 abstract pivoted to the lever, and means for operating the lever, substantially as specified.

3. A pianissimo device for piano-actions composed of a key, a capstan device, an elbow-piece having a foot that is supported upon the 80 capstan device, a lever pivoted to the elbow-piece, an abstract pivoted to the lever, a transverse rod engaging the lever, a hammer-rail, and a hanger which is adjustably secured to the hammer-rail and to the transverse rod, 85 substantially as specified.

4. A pianissimo device comprising a key, a capstan device, an elbow-piece supported on the capstan device, a compensator-lever pivoted to the elbow-piece, an abstract pivoted 90 to the lever, a link for guiding the abstract, and means for operating the lever.

5. A pianissimo device comprising a key, a capstan device, an elbow-piece on the capstan device, and an abstract linked to the elbow-piece, said elbow-piece having a socket 95 or seat for retaining the abstract.

6. A pianissimo device comprising a key, a capstan device, an elbow-piece on the capstan device, and an abstract, said elbow-piece 100

being linked to the abstract and loose or free with respect to the rest of the action.

7. A pianissimo device comprising a key having a capstan device, an abstract having a link pivoted to a fixed point, a compensating lever pivoted to the abstract, and a freely-movable elbow-piece joined to the compensating lever and resting on the capstan device.

In testimony whereof we have hereunto set our hands in the presence of two subscribing ^{to} witnesses.

WILLIAM KRETER.
CHARLES KRETER.
